Primary Examiner — Abraham Bahta*(74) Attorney, Agent, or Firm* — Harness, Dickey & Pierce, P.L.C.**CLAIM**

The ornamental design for a bag closure construction, as shown and described.

DESCRIPTION

FIG. 1 is a front view of a bag closure construction showing intact perforations in accordance with the design; FIG. 2 is a rear view thereof;

FIG. 3 is a front view thereof showing torn perforations; and, FIG. 4 is an enlarged view of the perforations shown in FIG. 1.

The bag closure construction is of no appreciable thickness and the opposite side thereof is symmetric with the shown front view. Boxes (□) are understood to represent perforations.

The broken lines present form no part of the claimed design.
